United States Patent Office

Des. 229,125
Patented Nov. 6, 1973

229,125

BICYCLE TRAILER

Ronald N. Davis, Stamford, Conn., assignor to
Cannondale Corporation, Stamford, Conn.

Filed Sept. 28, 1971, Ser. No. 184,648

Term of patent 14 years

Int. Cl. D12—10

U.S. Cl. D90—3

FIG. 1

FIG. 2

FIG. 4

FIG. 3

FIG. 1 is a perspective view of a bicycle trailer showing my new design;

FIG. 2 is a front elevational view thereof;

FIG. 3 is a rear elevational view thereof; and

FIG. 4 is a bottom plan view thereof.

I claim:

The ornamental design for a bicycle trailer, as shown.
